UNITED STATES PATENT OFFICE.

LARKIN J. MEAD, OF AURORA, ILLINOIS, ASSIGNOR TO AURORA CORSET COMPANY, OF AURORA, ILLINOIS, A CORPORATION OF ILLINOIS.
CORSET.

1,090,932.

Specification of Letters Patent. Patented Mar. 24, 1914.

Application filed October 7, 1912. Serial No. 724,273.

To all whom it may concern:

Be it known that I, LARKIN J. MEAD, a citizen of the United States, and a resident of Aurora, in the county of Kane and State of Illinois, have invented certain new and useful Improvements in Corsets; and I do hereby declare that the following is a full, clear, and exact description thereof, reference being had to the accompanying drawings, and to the letters of reference marked thereon, which form a part of this specification.

This invention relates to an improvement in corsets and consists of the matters herein-after described and more particularly pointed out in the appended claim.

The invention relates particularly to that type of corset having the lacing in front and which is provided with a shield back of the lacing to bridge the open space exposed by the lacing and confine and protect from protruding that part of the body or undergarment of the wearer which is covered by the lacing.

In the drawings: Figure 1 is a perspective view representing my improved corset in place on the body of the wearer before the parts thereof have been adjusted to their final position. Fig. 2 is a view representing a partial transverse section through the front of the corset body and shield as it appears when all parts thereof are in their final position. Fig. 3 is a view in front elevation of the shield of my improved corset. Fig. 4 is a fragmentary perspective view illustrating the means for attaching the margins of the shield to the corset body.

Referring to that embodiment of my invention illustrated in the accompanying drawings, 5 indicates the corset body which opens in front. Said body is provided adjacent one margin 5^a with a stiffening strip 6 provided with a vertical row of eyelets 6^a.

7 indicates a stiffening strip having eyelets 7^a, the same being connected with the stiffening strip 6 by means of a lacing 8 which passes through the eyelets 7^a, 6^a, in such manner so that the space between the stiffening strips 6 and 7 may be adjusted to the desire and comfort of the wearer. The stiffening strip 7 is adapted to be detachably connected to a stiffening strip 9 secured in the margin 10 of the corset body to close the corset in a familiar manner, the stiffening strips 7 and 9 being provided with

co-acting members 11 and 11^a of suitable hooking devices.

12 indicates a shield made of cloth adapted to lie beneath the lacing and next to the body when the corset is in place upon the body of the wearer. Said shield has margins 12^a, 12^b which are adapted to be detachably secured to the inner surface of the stiffening strips 6 and 7. Both margins 12^a and 12^b of the shield have stiffening members 12^x, 12^y preferably of whalebone or the like, which prevent any wrinkling of the margins, thereby eliminating discomfort to the wearer and giving "body" to the shield as a whole. To the front face of the lateral marginal parts 12^a, 12^b are secured snap fasteners 13, 13, the same being adapted for co-acting engagement with suitable snap sockets 14, 14 on the stiffening ribs 6 and 7, respectively. This construction provides a detachable connection between the shield and the parts of the corset at each side of the lacing whereby said shield may be attached to the corset in such manner as to lie underneath the lacing. A portion of the shield is formed by a strip of coarse netting 15 which is preferably located along the central or median line thereof and is secured by stitching at its lateral edges to the more flexible part of the shield. The shield is corded on both sides of the strip of netting 15, the said cord extending in closely spaced parallel vertical rows 16 which are stitched in pockets formed in the body of said shield 12. This construction provides a superior stiffening arrangement which prevents the protruding of the soft folds of the body through the lacing while at the same time obviating the discomfort to the wearer of the more rigid stiffening devices as whalebone or steel and the like as heretofore used. At the upper and lower margins of the shield 12 is secured binding tapes 17, 17, which assist in retaining the original shape of the shield and also preventing wear at the margins.

In the use of my improved corset, the shield member is detachably secured in position to the stiffening members 6 and 7 by means of the co-acting snap members 13 and 14. The shield member 12 is of a width greater than the space between the stiffening members 6 and 7 and accommodates itself to the space between the same. After the shield member 12 is in place, the margin

nal parts of the corset body may be grasped by the hands and secured in the usual manner.

It is apparent that a corset made in accordance with my invention has many advantages. The lacing may be adjusted in the usual manner and in making the shield member detachable from the corset body, will readily allow of laundrying of said shield and replacing the same by a new one if so desired. In addition the corset may be used with or without the shield to suit the wearer.

I claim as my invention:—

- 15 In a corset, in combination with a body opening in front and having a stiffening strip provided with eyelets at one margin, a second stiffening strip having eyelets spaced from said first mentioned stiffening strip,
- 20 lacing connecting the eyelets of the first and second mentioned stiffening strips, coacting members of attaching devices carried respectively on said second mentioned stiffen-

ing strip and the other margin of said corset body, a shield member adapted to lie beneath the lacing and coacting devices placed respectively on the margins of said shield and on said corset body for detachably connecting the lateral margins of said shield to said stiffening members, said shield member having stiffening members of whalebone and the like adjacent its lateral edges inside of the lines of the co-acting members of the attaching devices thereon and a centrally disposed non-rigid stiffening member consisting of a strip of netting having a plurality of closely spaced parallel rows of cording arranged adjacent thereto.

In testimony, that I claim the foregoing as my invention I affix my signature in the presence of two witnesses, this 4th day of October A. D. 1912.

LARKIN J. MEAD.
